UNITED STATES PATENT OFFICE.

GEORGE A. HIGGINS, OF NEW YORK, N. Y.

IMPROVEMENT IN COOLERS FOR WATER, &c.

Specification forming part of Letters Patent No: 122,384, dated January 2, 1872; antedated December 16, 1871.

To all whom it may concern:

Be it known that I, GEORGE A. HIGGINS, of the city and State of New York, have invented and made an Improvement in Coolers for Water, &c.; and the following is declared to be a correct description thereof.

Coolers for liquids have been made with a vessel for containing ice introduced into the liquid to be cooled, but to prevent the liquid to be cooled running into the vessel containing the ice an elastic packing has been employed, or else the ice-vessel could not be entirely submerged.

My invention is made with reference to submerging the ice-vessel in the liquid to be cooled without the use of an elastic packing and without the liquid to be cooled mixing with the water from the ice.

I also arrange the water-cooler so that only the coolest water is drawn off and the warmth of the external air and of the water above the ice-vessel has very little influence upon the ice itself, thereby the ice will not melt as rapidly as heretofore.

In the drawing I have shown a vertical section of my said cooler.

The vessel *a* for the liquid to be cooled is of suitable size and shape. The external case *b* and space *c*, for non-conducting material, are as usual; but the bottom portion *b'* of said case is enlarged, so as to give a larger space for the reception of non-conducting material *c'* around the lower part of the vessel *a*, because the ice is applied to cool the lower part of the liquid in *a*, hence the cooler can be lighter by making the non-conducting space *c* narrower where the water is but little cooled and but little non-conducting material is required. The non-conducting material employed may be of any desired character. The pipe *e*, to the faucet *f*, commences at or near the middle of the bottom of the vessel *a*, and rises within the space containing non-conducting material, in order that the faucet *f* may be sufficiently high to introduce a tumbler under the same; and this is no detriment so far as drawing off, almost all the water from the vessel *a*, because the ice-vessel introduced at the bottom of the vessel *a* displaces so much water that it will run from the faucet *f*, when but little remains in

said vessel *a*, thereby the portion of the cooler that is below the faucet is availed of instead of being useless, as heretofore. The ice-holder or vessel *g* is made of two cylinders with heads, the vessel *g* being of a size to allow the vessel *h* to sit over the same and form for it a cover. The cover *h* hence will confine any air that may be within it and the vessel *g*, so that said air cannot escape when the vessels *g* and *h* are immersed, therefore the liquid in the vessel *a* cannot get into the vessels *g* *h* to mix with the ice or the water thereof. The ice-vessel may be of greater or less capacity, as the one cylinder being within the other they can be slipped more or less into each other, according to the size of the piece of ice inserted. A catch, *k*, may be employed to hold the cover *h* upon the ice-vessel *g*, and when inserted in the water-cooler the rod *l* placed diagonally across the cooler with the upper end beneath a catch or depression, at *i*, serves to hold the ice-vessel down to place, but allow of said ice-vessel descending still further as the water is drawn off.

When this cooler is in use the water around the ice-vessel only is cooled in consequence of being at the bottom of the liquid; hence there is no loss of ice in keeping any more water cool than is required for immediate use, and as the water is drawn off the same is cooled progressively as it comes into contact with the ice-vessel.

When this ice-vessel is applied to cool milk and similar material it is to be allowed to float therein, so as to cool the entire mass for preventing injury by the warmth thereof.

I claim as my invention—

1. The ice-vessel *g* with the cylindrical cover *h* surrounding said vessel *g*, and retaining the air of the said ice-vessel to prevent the liquid to be cooled passing into the same, as set forth.

2. The vessel *a*, made with a surrounding casing *b' b* and inclosing the pipe *e*, as set forth, so that there is a thicker space for non-conducting material surrounding the lower part of the vessel *a*, for the purposes set forth.

3. The pipe *e* passing from the bottom of the vessel *a* and up through the non-conducting material to the faucet *f*, so that said fau-

cet will be at the necessary height above the bottom of the water-cooler, for the purposes set forth.

4. The ice-vessel *g* and cover *h*, combined with the movable rod, placed diagonally beneath the catch *i*, for the purposes and as set forth.

Signed by me this 29th day of May, A. D. 1871.

GEORGE A. HIGGINS.
